UNITED STATES PATENT OFFICE

168,249

TRANSPARENT CONTAINER FOR SOLUBLE CRYSTALS

Herbert J. Atkinson, Sudbury, Mass.

Application April 24, 1952, Serial No. 19,461

Term of patent 14 years

(Cl. D58—12)

To all whom it may concern:

Be it known that I, Herbert J. Atkinson, a citizen of the United States, residing at Sudbury, in the county of Middlesex and State of Massachusetts, have invented a new, original and ornamental Design for Transparent Container for Soluble Crystals, of which the following is a specification, reference being had to the accompanying drawing, forming part thereof.

Fig. 1 is a perspective view of a container, showing my new design;

Fig. 2 is plan view thereof;

Figs. 3 and 4 are sectional views taken along the lines 3—3 and 4—4 respectively in Fig. 1, with the corner connecting posts removed.

I claim:

The ornamental design for a transparent container for soluble crystals, as shown.

HERBERT J. ATKINSON.
